CLAIM

The ornamental design for a spacer, substantially as shown and described.

DESCRIPTION

FIG. 1 is a left side elevational view of a spacer showing my new design;
FIG. 2 is a front elevational view thereof;
FIG. 3 is a right side elevational view thereof;
FIG. 4 is a bottom plan view thereof;
FIG. 5 is a top plan view thereof;
FIG. 6 is a sectional view taken on line 6—6;
FIG. 7 is a sectional view taken on line 7—7;
FIG. 8 is a sectional view taken on line 8—8; and
FIG. 9 is a perspective view; and
FIG. 10 is a perspective view taken 180° from FIG. 9.
